Des. 242,515

Patented Nov. 30, 1976

242,515

FOOD SERVING TRAY

George K. Shumrak, 17 Fox Hill Drive, Natick, Mass.
01760, and Anthony Mack, 13 Hillview Road, North
Reading, Mass. 01864

Filed May 16, 1975, Ser. No. 578,201

Term of patent 14 years

Int. Cl. D7—99

U.S. Cl. D7—38

FIG. 1

FIG. 2

FIG. 3

FIG. 4 Des. 242,515

Page 2 of 2

FIG. 5**FIG. 6****FIG. 7****FIG. 8**FIG. 1 is a perspective view of a food serving tray;
 FIG. 2 is a top plan view thereof;

FIG. 3 is a front elevation view thereof;

FIG. 4 is a left side elevation view thereof;

FIG. 5 is a right side elevation view thereof;

FIG. 6 is a bottom plan view thereof;

FIG. 7 is a cross-sectional view of the food serving tray taken along section line 7-7 of FIG. 1; and

FIG. 8 is a cross-sectional view of the food serving tray taken along section line 8-8 of FIG. 1.

The rear elevation of the food serving tray (not shown) is the mirror image of the front elevation illustrated in FIG. 3.

All of the ribs shown in the bottom plan view are of the same height as those shown in FIG. 8.

We claim:

The ornamental design for a food serving tray, as shown and described.
